(57) **CLAIM**

The ornamental design for a portion of a display screen with animated graphical user interface, as shown and described.

DESCRIPTION

FIG. 1 is a front view of a first image of a first embodiment of a portion of a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a first image of a second embodiment of a portion of a display screen with animated graphical user interface showing our new design;

FIG. 7 is a front view of a second image thereof;

FIG. 8 is a front view of a third image thereof;

FIG. 9 is a front view of a fourth image thereof;

FIG. 10 is a front view of a fifth image thereof;

FIG. 11 is a front view of a first image of a third embodiment of a portion of a display screen with animated graphical user interface showing our new design;

FIG. 12 is a front view of a second image thereof;

FIG. 13 is a front view of a third image thereof;

FIG. 14 is a front view of a fourth image thereof; and,

FIG. 15 is a front view of a fifth image thereof.

In the first embodiment, the appearance of the transitional image sequentially transitions between the images shown in FIGS. 1 through 5. In the second embodiment, the appearance of the transitional image sequentially transitions between the images shown in FIGS. 6 through 10. In the third embodiment, the appearance of the transitional image sequentially transitions between the images shown in FIGS. 11 through 15.

The outer broken line rectangle showing of the mobile device as well as features of the mobile device are included for the purpose of illustrating environmental structure, the inner broken line rectangle showing of a display screen and all other broken lines showing portions of the graphical user interface are included for the purpose of illustrating portions of the article; broken lines form no part of the claimed design.
